UNITED STATES PATENT OFFICE

2,468,668

KNITTED FABRIC

Henry Harold Holmes, Leicester, England, assignor to Wildt and Company Limited, Leicester, England, a British company

Application October 9, 1946, Serial No. 702,180
In Great Britain October 19, 1945

5 Claims. (Cl. 66—180)

1

This invention relates to knitted fabric and has for its object to provide an improved terry loop fabric, as will be hereinafter described.

The expression "knitted fabric" is to be regarded generically as including not only fabric knitted in lengths, such as for manufacture subsequently into garments, but also knitted articles and garment lengths knitted separately, or in string formation, where the context so admits, as will be recognised by those skilled in the art.

As is well known, terry loops are formed from a thread or threads fed to the needles of a knitting machine conjointly with a yarn or yarns, for example in plating relation, by drawing longer sinker loops of the thread or threads so that such loops project from one surface of the fabric and provide a soft feel, or "plush" or "pile" effect, which may be enhanced by combing or brushing the loops.

For the purpose of conciseness and distinction in the following further description and in the appended claims the expression "thread" will be used with reference to the terry loops and the term "yarn" will be employed in respect of regularly knitted primary stitches.

In order that the invention may be more clearly understood and readily carried into practical effect examples of the improved knitted fabric will now be described with reference to the accompanying drawings, wherein:

Figure 1 is a face view, drawn to a greatly magnified scale, of a portion of knitted fabric incorporating terry looping.

Figure 2 is a sock knitted in accordance with this invention.

Figure 1 illustrates, by way of example, the inside of a piece of knitted fabric incorporating features of the invention. As will be seen, the fabric is knitted throughout of a ground yarn G and a terry thread T. The portion M is intended to represent heel, toe or foot bottom fabric of a knitted article of hosiery, the adjoining portion O representing instep fabric. The entire portion M is plain knitted with terry loops TL produced throughout the area to provide what may conveniently be called "half-round terry." The reference letter N indicates needle loops and the letter S sinker loops of the ground yarn G, the terry loops TL being constituted by elongated sinker loops of the thread T formed over the sinker loops S.

The instep portion O is divided into three adjoining panels, viz., a rib panel P of three ribs R, R₂ and R₃, a panel Q of links-link fabric with loops knitted in both rib and plain directions, and

2

a panel S of plain ground fabric interspersed with selected terry loops such as TL₁ constituting a pattern effect or design.

The invention also includes as a feature—as produced on a circular seamless hose machine with co-axial needle cylinders including double-ended needles operated by means of sliders—a knitted article of hosiery such as a three quarter hose, half hose or sock comprising a welt, a 1 x 1 or other rib top, a leg with broader rib or riband/or links-links pattern interspersed with selected terry loop effects in the plain stitch portions or panels, and a terry heel, sole and toe. If desired a knitted article of hosiery may include a terry high heel portion or/and a terry ring toe. As regards tubular fabric with selected terry loop effects the same is reversed after knitting to expose the terry pattern effect or design. A specific example of a sock made in accordance with the invention is depicted in Figure 2. This sock comprises a welt w followed by a 1 x 1 rib top rt, a leg l composed of spaced rib panels rp, intervening panels ll of selective transfer (links-links) and panel st of selective terry, a high heel hh of half-round terry, a terry heel h, reinforced or otherwise, and a foot comprising an instep i patterned in the same manner as the leg l, a terry foot bottom fb, a terry ring toe t and a terry toe tl, reinforced or otherwise, according to requirements. lc represents the linking courses.

What I claim then is:

1. Knitted fabric with pattern effects constituted by terry looping in at least one desired area, said pattern effects being interspersed with both rib stitch and also links-links stitch effects, and with terry loops throughout at least one selected section of the fabric.

2. A knitted article of hosiery comprising a welt, a rib top, a leg with rib and links-links patterns interspersed with selected terry loop effects in plain stitch panels, and a terry heel, sole and toe.

3. A knitted article of hosiery according to claim 2, which includes a terry high heel portion and a terry ring toe.

4. A knitted article of hosiery comprising a welt, a rib top, a leg and instep with spaced rib panels and intervening panels of links-links patterns and plain stitch panels patterned with selected terry loop effects, a terry high heel, a terry heel, a terry foot bottom, a terry ring toe and a terry toe.

5. A knitted article of hosiery comprising a welt, a rib top, a ribbed leg and instep of a broader rib than the said top and having pattern effects

constituted by terry looping in the plain stitch panels, and a terry heel, sole and toe.

HENRY HAROLD HOLMES.
